CONTAINER

Irving Florman, New York, N. Y.

Application November 16, 1934, Serial No. 753,396

4 Claims. (Cl. 206—37)

My invention relates to containers and more particularly to containers of the pocket type especially, but not necessarily, adapted for holding cosmetic materials such as face powder.

5 One object of my invention is to provide a container of this type which is easy to operate and convenient in use.

A further object is to provide a container which is substantially sealed in closed position, so as to 10 prevent the escape of powder or other granular materials from the container, while avoiding the use of tight fitting covers or latches such as are usually necessary for this purpose. More particularly, I provide a device which will prevent 15 powder, loose tobacco or the like from escaping into the pocket or pocketbook of the user when the container is closed.

Another feature of the invention, and one which makes it particularly suitable for use as a compact, is the fact that the procedure necessary for 20 opening or closing the container imparts a series of vibrations which will agitate the powder and cause it to assume the flat form which it should have when it is to be used.

25 Further objects and advantages will appear more fully from the following description particularly when taken in conjunction with the accompanying drawing which forms a part thereof.

In the drawing:

30 Fig. 1 is a top plan view of my container in closed position.

Fig. 2 is a cross section on the line 2—2 of Fig. 1.

Fig. 3 is a side elevation of the device in open position.

35 Fig. 4 is a cross section on the line 4—4 of Fig. 2.

The container comprises in general a thin casing of substantially rectangular shape, having a flat bottom wall 2 and substantially flat side wall members 4. The end walls 6 are curved, being

40 preferably substantially semi-circular in cross section. The top of the container has an opening 8, this opening preferably extending across the whole space between the upper edges 10 of the end walls 6. The side walls are composed of inner members

45 12 preferably secured rigidly to the edges of the bottom wall 2, which form the wall of the chamber, a spacing block 14, and an outer casing member 16, these three parts being secured together by rivets 18. The members 16 are preferably of 50 slightly greater dimensions than, and form a flange around the inner members 12, and the edges of the members 16 are bent inwardly as at 19, thus forming a continuous inwardly directed groove 20 around the whole of the container.

55 The open top of the container may be closed by

means of a cover 22 hinged at 24 along the upper edge of one of the end walls, and normally held in elevated or open position by a spring 26. The inner face of this cover is provided with a suitable reflecting surface, as for instance a mirror 28. It is obvious that when the cover is open the mirror can be used to aid in the application of the powder.

In order to hold the cover in closed position when the device is not in use, and to prevent the escape of granular materials from the container, 10 I provide a shutter or flexible member composed of a plurality of narrow strips 30 of hard plastic material arranged in close side by side relation on a sheet 32 of flexible material such as cloth. The length of these strips is substantially equal to the 15 distance between the outer side wall members 16, and the ends of the strips comprise reduced portions 34 which extend into the grooves 20, and are guided and held thereby. The main body portions of the strips 30 are of such thickness as to 20 extend a slight distance above the flanges 19.

The total length of the shutter member is greater than the width of the opening 8, but is not more than the combined length of the bottom wall 2 and end walls 6.

Assuming that the device is in the closed position such as shown in Fig. 1, and that it is desired to open the same, the shutter is moved by hand to the position shown in Fig. 3. The grooves 20 cause the shutter to follow the outline of 30 the container at all times and to pass around the curved ends to the bottom side thereof. As soon as the shutter uncovers the cover 22, spring 26 will raise the cover to open position. The mirror can then be used and the contents of the 35 container are available.

To close the device, the cover is depressed by hand and the shutter is then pushed around by hand until it again assumes the position shown in Fig. 1. In this position, it quite evidently prevents the cover from rising. At the same time, the cover fits tightly enough to hold any loose powder or other loose granular material within the package and thereby keeps such material from falling into the space in which it is carried by the user.

Within the container, I may provide a powder holder 36, comprising a frame of flexible material which fits tightly within the casing and carries a closure sheet of gauze of the usual type. 50 A puff or applicator 38 may be contained in the space above the shield, so that the device is a complete arrangement for powdering the face.

While I have described my container as particularly applicable to compacts or containers for 55

cosmetics, it is quite obvious that it may be used for other purposes within the scope of the invention. I therefore wish it to be clearly understood that the description and drawings of the embodiment disclosed are intended to be merely an example of the invention, and that I do not intend to be limited thereby except within the scope of the appended claims.

I claim:

- 10 1. A container comprising a bottom wall, side walls, end walls, and a top, said container having an opening in its top, a continuous flexible closure member of greater length than the length of said opening arranged to slide with respect to said opening, said side walls comprising inner and outer members, means for holding said members in spaced relation, said outer members being of slightly greater width than said inner members and having inwardly directed flanges at opposed edges thereof, said flanges forming with said inner members endless grooves for guiding said flexible closure member in its sliding movement.
- 15 2. A container comprising a bottom wall, side walls, end walls, and a top, said container having an opening in its top, a continuous flexible closure member of greater length than the length of said opening arranged to slide with respect to said opening, said side walls comprising inner members and outer members, means for holding said members in spaced relation, said outer members being integrally secured to said bottom wall, means for securing said side wall members together to form a unit, said outer members being of slightly greater width than said inner members and having inwardly directed flanges at opposed ends thereof, said flanges forming with said inner members endless grooves for guiding said flexible closure member in its sliding movement.

3. A container comprising a bottom wall, side walls, rounded end walls, and a top, said container having an opening in its top, a continuous flexible closure member of greater length than the length of said opening but of lesser length than the combined length of the bottom and side walls, said side walls comprising outer and inner members, means for holding said members in spaced relation, said outer member having inwardly directed flanges at opposed ends thereof, said flanges extending beyond said inner members and said bottom walls and forming with said inner members endless grooves, said closure member having portions slidably guided in said grooves whereby said closure member is guided to slide on the outer surface of the container to open or close said opening.

4. A container comprising a bottom wall, side walls, rounded end walls, and a top, said container having an opening in its top, a continuous closure member of greater length than said opening but of lesser length than the combined length of the bottom and side walls, said closure member being arranged to slide with respect to said opening, said side walls comprising outer and inner members, means for holding said members in spaced relation, said outer members having inwardly directed flanges at opposed ends thereof, said flanges extending beyond said inner members and said bottom walls and forming with said inner members endless grooves, said closure member comprising a plurality of rigid elements extending in a direction parallel to said end walls and having portions extending within said grooves and guided thereby, and a sheet of flexible material beneath said elements, said elements being secured to said sheet in closely adjacent relation.

IRVING FLORMAN.
